United States Patent Office.

J. H. ALDRICH, OF NASHUA, NEW HAMPSHIRE.

Letters Patent No. 65,089, dated May 28, 1867.

IMPROVEMENT IN WAGON BODIES.

The Schedule referred to in these Letters Patent and making part of the same.

TO ALL WHOM IT MAY CONCERN:

Be it known that I, J. H. ALDRICH, of Nashua, county of Hillsborough, State of New Hampshire, have invented a new and useful Improvement in Cart or Wagon Bodies. The following is a correct description invented a new and useful Improvement in Cart or Wagon Bodies. The following is a correct description thereof, with reference being had to the accompanying drawings, and letters marked thereon, making a part of this specification.

The novelty of my invention consists in the floor extending around all of the wheels upon the same level, and at the same time the wheels may project above said floor. I will describe its construction and operation.

Figure 1 is a plan, and

Figure 2 a side elevation.

In fig. 1, letters *a a* are sills placed outside the wheels, and are supported by sills at right angles, which extend out forward and back of said wheels. *B B* are caps which enclose the wheels from the load. When this improvement is applied to a four-wheeled carriage the position of said caps *B B*, as shown in fig. 2, are easily changed by means of screw-bolts which firmly secure them in place. By this arrangement bulky loads may be broad and low, and less liable to accident.

I am aware of the various modes by which loads are widened after getting above the wheel, all of which I disclaim.

What I claim as my invention, and desire to secure by Letters Patent, is—

The arrangement and combination of said sill *A* with cap *B*, for the purpose herein described.

J. H. ALDRICH.
